GEORGE M. HOPKINS, OF ALBION, NEW YORK.

Letters Patent No. 87,102, dated February 23, 1869.

IMPROVEMENT IN LOW-WATER INDICATORS.

The Schedule referred to in these Letters Patent and making part of the same.

Be it known that I, GEORGE M. HOPKINS, of Albion, in the county of Orleans, and State of New York, have invented a new and useful Improvement in Low-Water Indicators for Boilers; and I do hereby declare that the following is a full, clear, and exact description of the construction and operation of the same, reference being had to the annexed drawings, making a part of this specification, in which—

Figure 1 represents a vertical section.

Figures 2 and 3 represent modifications of a portion of the same.

The object of this invention is to provide an apparatus which is to be connected with a boiler at a given line, which shall alarm whenever the water in the boiler passes below said line.

I will proceed to describe my invention.

In the accompanying drawings, (see fig. 1)—

A is a tube, which is provided at its upper end with a valve-seat, B, to which is fitted the valve C.

D is a rod, extending through the valve C, and engaging with the stirrup E, by means of a screw cut upon its lower end.

F is a wire or strip of brass, or other expansive metal, the upper end of which is connected with the stirrup E, while the lower end is attached in any convenient manner to the tube A at G.

H is a cap, fitted to the upper end of the tube A, which covers the valve C, and its seat B, and is provided with an opening, I, connecting with the whistle J.

The rod D passes upward through the cap H, and is provided with a suitable head, K, beneath which is placed the spring L, the lower end of which rests upon the cap H.

M is a support for the thumb-screw N, placed immediately over the rod D.

The valve C is held firmly to its seat B by the wire F, upon which tension is produced, by turning the head K, operating the screw in the stirrup E.

The stirrup E is prevented from turning by the pins a a.

If it is desired to shorten the apparatus, it may be accomplished by passing the wire, or strip F, around the pulley O, as shown in fig. 2, or in place of the pul-

ley O, the wire may be cut, and connected by means of the lever P, as in fig. 3.

By multiplying the pulleys or levers, the apparatus may be shortened as much as is desired. In such case the end, G, of the wire, or strip F, may be attached at any desirable point.

The apparatus is connected to the boiler just above the line at which an alarm is desired.

The operation is as follows:

As long as the water in the boiler covers the end of the tube A, the water in the tube will remain comparatively cool. When the water drops below the end of tube A, the water passes out of it and steam enters. The temperature being thereby increased, the wire F expands, releasing the valve C, when the combined force of the spring L and the steam, opens the valve C, permitting the escape of the steam through the whistle J, causing an alarm.

When the apparatus has alarmed, the valve C may be forced down to its seat by means of the screw N. When the water in the boiler again covers the mouth of the tube A, the water is forced into it, and there being no circulation, it soon cools, and, when cool, the wire F is contracted, and the screw N should be loosened.

I am aware that expansion-rods have been used for the purpose of opening a valve for an alarm; therefore I do not desire to claim the opening of the valve by the expansion of the wire; but

What I do claim as my invention, and desire to secure by Letters Patent, is—

1. The wire, or strip F, in combination with the stirrup E, rod D, and tube A, substantially as set forth.

2. The arrangement of valve C, rod D, stirrup E, and spring L, substantially as shown and described.

3. The screw N, in combination with the above devices, as set forth.

Signed by me, this 11th day of December, 1868.

GEO. M. HOPKINS.
